(57) **CLAIM**

The ornamental design for a pneumatic tire, as shown and described.

DESCRIPTION

FIG. 1 is a perspective view of pneumatic tire showing our new design, it being understood that the tread pattern repeats circumferentially about the outer circumference and shoulder of the tire.

FIG. 2 is a front elevational view thereof.

FIG. 3 is a rear elevational view thereof.

FIG. 4 is a left side elevational view thereof.

FIG. 5 is a right side elevational view thereof; and,

FIG. 6 is a partial enlarged front elevational view thereof.
